UNITED STATES PATENT OFFICE.

JOHN W. DAVENPORT, OF RICHMOND, INDIANA.

KEYLESS LOCK.

No. 845,931.

Specification of Letters Patcnt.

Patented March 5, 1907.

Application filed September 19, 1906. Serial No. 335,193.

To all whom it may concern:

Be it known that I, JOHN W. DAVENPORT, a citizen of the United States, residing in the city of Richmond, in the county of Wayne 5 and State of Indiana, have invented a new and useful Keyless Lock, of which the following is a complete and accurate specification.

This invention relates to permutation-locks; and my object is to provide a lock 10 which is simple in construction and practical in its application and operation, being positive in action, and which can be manufactured and sold at a comparatively low price.

A further object is to provide a keyless 15 lock capable of a wide scope of usefulness and efficiency, adapted to be opened upon the alinement of certain parts thereof, determinable by a prearranged combination known only to those authorized, and means 20 whereby the accidental finding of the combination is reduced to a minimum.

Other objects and particular advantages of my invention will appear in the course of the accompanying exposition thereof.

25 My invention consists in a permutation-lock embodying certain new and useful features and details of construction and relative disposition of the several parts substantially as described elsewhere in this specification 30 and in the legitimate combinations herein set forth.

The principles of my invention are herein shown as applied to a chest-lock; but it is not intended that this invention should be limited to this specific purpose, and in order that 35 the invention may be more fully understood I will now take up the description thereof in concrete detail, in which I will describe the invention and its operation as briefly and as 40 comprehensively as I may.

Referring now to the drawings broadly, Figure 1 shows an outside face view of my lock in operative position as applied to a chest or the like. Fig. 2 is a plan introspective view showing the parts in the position when the device is unlocked. Fig. 3 is a central horizontal sectional view of my lock as 45 taken on the line X X of Fig. 1 and showing the parts in the position when the device is locked. Fig. 4 is a detail view of the assembled disks removed from the body, but retained in their assembled positions. Fig. 5 is a detail vertical sectional view of the coupling members as taken on the line Y Y of 50 Fig. 2. Figs. 6, 7, and 8 are detail views,

each being of one of the washers for spacing the disks; and Figs. 9, 10, and 11 are detail views of the several disks.

Similar indices denote like parts throughout the several views.

Referring now to the invention in detail, the letter A denotes the front plate of my lock. The letter B denotes the back plate. The letter C denotes the base-plate. The letter D denotes the top plate, and the letters 65 E and F denote the two side plates, said parts together forming the case or inclosure for the working parts. The front plate A, the base-plate C, and the side plates E and F are integral—that is, formed of one piece of 70 metal—and the front plate A extends out at either side beyond the plates E and F and also down below the plate C, thereby forming a flange, and in like manner the plate B extends out beyond the plates E and F the 75 same distance as does the plate A.

The numeral 1 denotes the main spindle, which is permanently fixed at its rear end in the plate B and extends forward to near the plate A, but is not attached thereto, and an 80 aperture is formed through the plate A of a larger diameter and opposite to said spindle.

The numeral 2 denotes the master-disk, which is separated from the plate A by the boss 2', which is of less diameter than is the 85 disk 2, said boss being adapted to contact with the inner surface of the plate A and having a stem 2" extending therefrom through and slightly out beyond the face of the plate A, it passing through said aperture in the plate A. 90 Said disk, boss, and stem are preferably formed integral, as shown. An aperture is formed centrally through the disk 2 and which extends into the boss 2' to receive the otherwise free end of the spindle 1, as shown 95 in Fig. 3.

The indice 3 denotes a knurled knob secured to the outer portion of the stem 2", said knob being outside the plate A, as shown. Extending out, around, and from 100 the knob 3 is a plate 4, which may be integral therewith.

The numeral 5 refers to the circular dial, which is sunk in the face of the plate A, and around on its outer portion it is divided into 105 sixty equal spaces numbered in groups of five.

The indice 4' denotes a radial channel on the plate 4, which channel extends from the knob 3 out to the periphery of said plate, as 110

shown in Fig. 1, whereby the rotation of the knob 3 and the plate 4 will bring the channel 4' in alignment with each of the degree-marks of the dial 5.

5 The numeral 6 designates the intermediate disk, which is revolvably mounted on the spindle 1. Said disk 6 is of same dimensions as the disk 2, from which it is separated by the collar 7. Said collar is also mounted on the 10 spindle 1, being secured thereto by a set-screw 8.

15 The numeral 9 refers to the rear disk, which is revolvably mounted on the spindle 1. Said disk 9 is of same dimensions as the disks 2 and 6, and it is separated from the latter by the collar 10, which collar is also mounted on the spindle 1, being secured thereto by the set-screw 11. The disk 9 is separated 20 from the plate B by the collar 12, which collar is also mounted on the spindle 1 and is secured thereto by the set-screw 13.

25 From the above it will be noticed that the disks 2, 6, and 9 are spaced an equal distance apart and an equal distance from the plates A and B. Each of the disks 2, 6, and 9 is provided at one point in its periphery with a square indentation, as the indentations 14, 15, and 16, respectively.

30 Extending in an axial direction from the rear face of the disk 2 is the pin 17. Extending in an axial direction from the forward face of the disk 6 is the pin 18, and extending in an axial direction from the rear face of the disk 6 is the pin 19, said pins 18 35 and 19 being oppositely disposed with reference to each other and also with reference to the central aperture of the disk, and extending in axial direction from the forward face of the disk 9 is the pin 20. All of said pins 40 are equally distant from the center of the spindle 1. Additional apertures *a*, *b*, and *c* are formed in the rear face of the disk 2, to either of which the pin 17 may be moved from the present position in order to change the combination of the lock.

45 The numeral 21 designates the locking-plate, whose width is the same as the combined width of the disks 2, 6, and 9, together with the collars 7 and 10, as shown in Fig. 2. The thickness of the locking-plate is slightly less than the width of the indentations 14, 15, and 16. Three teeth *e*, *f*, and *g* are formed by the left-hand end of said plate 21, said teeth being adapted to fill the respective indentations 14, 15, and 16, as shown in Fig. 2, or to be moved forward out of engagement with said indentations, as shown in Fig. 3. Extending outward from the sides of the plate 21 and located near the right-hand end 55 thereof are the respective front and rear pivots 21' and 21'', which are mounted to slide in an axial direction through apertures therefor in the respective plates A and B. The helical spring 22 encircles the pivot 21'', 60 and it is seated at one end against the rear

edge of the plate 21, with its other end against the inner face of the plate B, the resiliency of said spring tending at all times to normally retain the plate 21 forward to its limit—that is, to the position shown in Fig. 3. On the outer end of the pivot 21' is secured the push-button 23, which normally stands out from the face of the plate A, as shown in Fig. 5.

65 Extending across through the plate 21 parallel with the spindle 1 and located near the base of the teeth *e*, *f*, and *g* is an aperture 70 to receive the bar 24, which bar is secured across and to the plates A and B and parallel with the spindle 1 and the pivots 21' and 21''. Said bar 24 is simply to support the left-hand 75 portion of the plate 21 and on which bar said plate may slide back and forth. Rigidly secured in the plate 21 and extending upwardly thereabove is the locking member 25, having a tapering head and a horizontal shoulder, as 80 shown in Fig. 5.

85 The letter G denotes a portion of the front vertical side of a chest or the like, and the letter H denotes a portion of the front edge of the lid, which is adapted to be raised and lowered. Set in and secured in the contact 90 edge of the lid H centrally of and opposite to the lock is the plate 26, (shown in Fig. 1,) and extending down from the plate 26 is the locking member 27, similar to but oppositely disposed from that of the member 25, an aperture D' being formed through the plate D, through which the member 27 may pass to the interior of the lock.

95 The manner of securing the lock in place is substantially as follows: A notch is cut out of the front G, extending from the upper edge thereof downward the distance to allow the surface of the plate D to be even with the upper edge of the front G, said notch being of a length such as to receive the outer faces of the side plates E and F, the thickness of the front G being the same as the distance between the plates A and B. After said notch is formed in the front G the lock may be 100 pressed down into said notch, and the plate D is let in flush with the upper edge of the front G, where it may be secured by screws, as the screw I, the other screw not being shown. The lock is further secured in place 105 by four plain head-bolts, (denoted by letters J, K, L, and M.) These bolts pass through apertures therefor in the flanges formed by the outer ends of the members A and B and also through the material of the front G and 110 are supplied with nuts on their rear ends, which cannot be removed when the chest is closed. The position of the plate 26 is such that when the lid H is closed the member 27 115 will pass through the aperture D' and engage the member 25 in the manner shown in Fig. 5.

120 Operation: The parts being assembled and placed in position in connection with a chest or the like, it will be apparent that if the lid 125

130

be closed down, as in Fig. 1, that the locking members will engage with each other, as shown in Fig. 5, and then if the knob 3 be given a few turns to the right it will be apparent that the plate 21 cannot then be pushed back and that the locking members 25 and 27 cannot then be disengaged until this is done—that is to say, not until the indentations 14, 15, and 16 are alined with each other and in registering position with the teeth *e*, *f*, and *g*. It should be noticed that as the knob 3 is rotated in either direction that it will carry with it the disk 2, and at a certain point the pintle 17 of the disk 2 will engage the pintle 18 of the disk 6, which will cause the disk 6 to be rotated with the disk 2, and continuing the rotation in the same direction the pin 19 of the disk 6 will engage the pin 20 of the disk 9, thereby causing the disk 9 to be rotated with the disks 2 and 9; but should the knob 3 now be rotated in the opposite direction then the disks 6 and 9 will be left inactive until the disk 2 has completed one revolution, when the disk 6 will be taken up and rotated therewith until the disk 6 has completed one revolution, when the disk 9 will be taken up and revolved therewith. Desiring now to unlock the chest with the present combination the operations are substantially as follows: The knob 3 is given a few turns to the right in order to gather up all the disks. The knob 3 is now turned to the right until the channel or pointer 4' is alined with the mark "eighteen" of the dial, as in Fig. 1, which will bring the indentation 16 in registering alinement with the tooth *g*; but at the same time the indentations 14 and 15 would be out of alinement with their respective teeth *e* and *f*. Consequently the plate 21 could not be pressed back. The knob 3 is now turned to the left one complete revolution and then continued in the same direction until the pointer 4' is in alinement with the mark "thirty" of the dial. This last movement will not have moved the disk 9, but it will have moved the disk 6, whereby the indentation 15 will be in alinement with the tooth *f*; but now the indentation 14 is not in alinement with the tooth *e*, and to accomplish this the knob 3 is now turned to the right until the pointer 4' is in alinement with the mark "sixty" of the dial. Now as the indentations 14, 15, and 16 are all in alinement with each other and with the teeth *e*, *f*, and *g* it is apparent that by pressing in the push-button 23 that the teeth *e*, *f*, and *g* will enter the respective indentations 14, 15, and 16, thus causing the member 25 to be carried to the rear, and therefore out of locking engagement with the member 27, thereby allowing the lid to be raised, and consequently the member 27 withdrawn from the lock. When the push-button 23 is released, then the spring 22 will return the member 25 to its former locked and normal

position, whereby when the lid is closed the member 27 will automatically engage with the member 25.

It is apparent that a great many variations in the combination may be made from that above given—as, for instance, by changing the pin 17 to one or the other of the apertures *a*, *b*, or *c*.

It is evident that my lock although very strong and durable, positive in action, and easily attached, yet it can be made very cheaply and also that my lock is practically noiseless and in opening it no click or other sound is given as a guide to the unauthorized, and I desire to have it understood that various changes may be made in the details of my lock in order to adapt it to various uses without departing from the spirit or the principles of this invention.

Having now fully shown and described my invention, what I claim, and desire to secure by Letters Patent of the United States, is—

1. A keyless lock comprising a casing, means for securing the casing in operative position, a permutation mechanism contained in the casing, a knob located outside the casing for operating the permutation mechanism, means for determining the operation of said knob, a locking-plate inside the casing adapted to be either secured or freed by the permutation mechanism, a spring for retaining said locking-plate in normal position, and a push-button located outside the casing for moving said locking-plate out of its normal position after being freed by the permutation mechanism, all substantially as shown and described and for the purposes set forth.

2. A permutation-lock comprising in combination, a casing having an exposed front plate containing a dial, means for securing the casing in position, a movable locking member extending upward inside the casing, a permanent locking member extending down into the casing adapted to interlock with the first-named locking member, a horizontally-movable plate carrying said upwardly-extending locking member, a push-button located outside the face of the casing and adapted to move said locking-plate inward, a spring adapted to normally retain the locking-plate outward and the locking members in engagement with each other, teeth formed on one end of the locking-plate adapted to be moved into and out of said indentations of the disks, means for spacing the disks apart, a knob outside the face of front plate and secured to one of said disks, a plate carrying a marker and secured to said knob and in contact with said dial, and means for bringing the indentations of the disks into alinement with each other and with the teeth of the locking-plate by the revolution of said knob, all substantially as shown and described.

3. In a keyless lock, the combination with

the case, a locking-plate, means outside the case for sliding the locking-plate in one direction, a spring inside the case for returning the locking-plate to its normal position, a fixed shaft inside the case, disks mounted on said shaft and each having an indentation in its periphery, collars secured to said shaft for separating said disks, forks extending out from one end of the locking-plate and normally resting between said disks and adapted to enter said indentations of the disks when said locking-plate is pressed in against the resiliency of said spring, means for rotating said disks together and for allowing each to make a revolution without actuating the others, and means for changing the relative revolutions of the disks, all substantially as shown and described.

4. A lock comprising a suitable casing, a dial formed on the face of the casing, a knob and pointer operative concentrically over said dial, a movable locking member extending upwardly inside the casing, a relatively permanent locking member extending downwardly into the casing and adapted to interlock with the first-named locking member, a horizontally-slidable plate carrying said upwardly-extending locking member, a push-

button located outside the face of the casing and adapted to move said locking-plate inward, a spring for returning the locking-plate to its normal position when said push-button is released, a shaft operative within the casing and carried with said knob and pointer, a series of disks revolvably mounted on said shaft with one of said disks continuously carried with the shaft, collars secured to said shaft and spacing said disks some distance apart, pins secured in the opposing faces of said disks to provide means whereby the indentations of the disks may be brought into alinement with each other by the rotation of said knob, teeth formed in one end of the locking-plate adapted to be moved into said indentations of the disks when said indentations are in alinement and to rest between the disks when said indentations are out of alinement, all substantially as shown and described.

In testimony whereof I have hereunto signed my name to this specification in the presence of two subscribing witnesses.

JOHN W. DAVENPORT.
